(No Model.)

J. C. BATES.
PLOW.

No. 540,711.

Patented June 11, 1895.

Fig. 2.

UNITED STATES PATENT OFFICE.

JOHN C. BATES, OF LAKE CITY, FLORIDA.

PLOW.

SPECIFICATION forming part of Letters Patent No. 540,711, dated June 11, 1895.

Application filed March 30, 1895. Serial No. 543,856. (No model.)

To all whom it may concern:

Be it known that I, JOHN C. BATES, a citizen of the United States, residing at Lake City, in the county of Columbia and State of Florida, have invented a new and useful Plow-Stock, of which the following is a specification.

This invention relates to improvements in plows; and has for its object to provide a landside which is adapted to have adjustable connection with the lower end of the stock and at the same time provide an extended bearing surface to receive shovels of various shapes and enable the latter to obtain a firm purchase against lateral tipping when the plow is in effective service.

A further purpose of the invention is to provide positive means for connecting the shovels of different shapes to the stock, where-
20 by they will be held securely against any ac-
cidental displacement in the operation of the plow.

For a full understanding of the invention reference is to be had to the accompanying drawings and the reference numerals thereon, taken in connection with the following description.

Figure 1 is a perspective view of a plow of ordinary construction, showing the applica-
30 tion of the invention thereto. Fig. 2 is a de-
tail view showing the means for securing the shovel to the stock. Fig. 3 is a detail view
of the improved landside. Fig. 4 is a top
plan view of the landside. Fig. 5 is a detail
35 view of the brace which is mounted upon the
bolt that connects the shovel to the stock and
which has a cross-head to extend over the up-
per edge of the said shovel to secure the same
from vertical displacement.

40 The plow beam 1, handles 2, and stock 3
may be of any desired construction and ar-
rangement, and the said stock is braced in
the ordinary manner by means of the stay 4.
The stock is composed of similar members 5,
45 between which the beam 1, stay 4, and verti-
cal portion 6 of the landside 7 are secured.

The landside 7 comprises an upwardly-ex-
50 tends portion 6 and a horizontal bar 8, the
latter having lateral flanges 9 at its lower
edge to obtain an extended bearing upon the
soil. These flanges 9 taper to the sides of the
bar 8 at the front end of the latter so as to

offer no resistance to the advancement of the plow, and gradually widen toward the rear end of the bar so as to provide a broad shoe 55 for the landside to run upon. The upwardly-extending portion 6 has laterally-extending flanges 10 which gradually taper from the upper end of the portion 6 to the sides of the bar 8 and form a broad seat for the shovel 11, 60 which may be single or double and have any shape usually given to the southern plow points, or shovels, used in the various sections of the country. The inner sides of the flanges 10 bear upon the front edges of the 65 members 5 of the plow stock, thereby dividing the strain equally upon the said members.

A longitudinal slot 12 is formed in the upwardly-extending portion 6 of the landside and receives a fastening bolt 13, by means 70 of which the said landside is adjustably clamped between the lower end portion of the plow stock members. When it is required to adjust the landside vertically, the fastening bolt 13 is loosened, thereby permitting the 75 landside to be moved to the required position, when, by tightening the said bolt 13, it will be held in the located position.

The shovel 11, which may be of any de-
sired pattern or form according to the nature 80
of the work for which the plow is designed,
is secured to the stock by means of a fasten-
ing bolt 14 and a hand nut 15, the bolt pass-
ing through an opening in the shovel and be-
tween the members of the plow stock. A fas-
tening brace 16 is curved in its length, and 85
has a cross head 17 at its front end to extend
over the upper edge of the shovel 11, and has
its rear end provided with an eye 18, through
which the threaded portion of the fastening 90
bolt 14 passes. The cross head 17 obtains an
extended bearing on the upper edge of the
shovel and prevents the latter turning on the
bolt 14.

It must be remembered that the various 95
forms of shovels differ in size, and to the end
that the landside may be successfully used
with each it is necessary that it be capable
of vertical adjustment so that the lower side
of the bar 8 may be approximately in the 100
same horizontal plane with the cutting edge
of the shovel, which is essential to the suc-
cessful operation of any plow. It will be seen
that the means herein set forth attain the de-

sired result in a simple and effective manner, and that a broad seat is provided for the shovel so as to brace the latter when in operation in opening or turning a furrow.

5 In order to adapt the invention to the various styles of plows now in use and attain successful results, it is obvious that changes in the form, proportion, and the minor details of construction may be resorted to without departing from the principle or sacrificing any of the advantages of this invention.

Having thus described the invention, what is claimed as new is—

1. The combination of a plow stock and a shovel, of a landside having an upwardly-extended portion provided with a longitudinal slot and laterally-extending flanges which are adapted to bear upon portions of the stock disposed on each side of the said upwardly-extended portion, and which form a broad seat for the shovel, the lower edge portion of the horizontal bar having lateral flanges to provide an extended surface for the landside to travel upon, and a fastening bolt to adjust-

ably secure the landside to the said stock, whereby the latter can be adapted to the size of the shovel, substantially as and for the purpose set forth.

2. In a plow, the combination with a stock comprising similar members and a shovel, of a landside having an upwardly-extended portion provided at its front edge with laterally-extending flanges, and having a slot, a fastening bolt passing through the members of the stock and the slotted portion of the landside to adjustably clamp the latter between the said members, and means for securing the shovel to the stock and upon the flanged portion of the landside, substantially as described and for the purpose set forth.

In testimony that I claim the foregoing as my own I have hereto affixed my signature in the presence of two witnesses.

JOHN C. BATES.

Witnesses:

W. M. IVES,

DUVAL SELPH.
